UNITED STATES PATENT OFFICE.

ARTHUR MAEHLER, OF CHICAGO, ILLINOIS.

ENAMELING OVEN.

Application filed February 17, 1923. Serial No. 619,669.

To all whom it may concern:

Be it known that I, ARTHUR MAEHLER, a citizen of the United States of America, residing at Chicago, in the county of Cook 5 and State of Illinois, have invented certain new and useful Improvements in Enameling Ovens, of which the following is a specification.

This invention relates to that type of drying or enameling apparatus in which an overhead endless carrier is used to carry the articles being treated in a continuous manner to a dipping means to be coated, and through a drying chamber to be dried or 10 enamelled, and more particularly to that form of such apparatus in which alternating series of dipping means and drying chambers are employed. The object of the present improvement is to provide a formation 15 and combination of parts in the upper portion of the apparatus adapted to conserve in an effective manner the heat within the drying or enameling chambers, and in which the returning portions of the endless carrier 20 are maintained in a heated condition during a return travel to the feeding end of the apparatus, so as to abstract but a minimum amount of heat in their passage into and through the drying chamber or chambers 25 and carrying the articles to be dried or enamelled, all as will hereinafter more fully appear.

In the accompanying drawings:—

Fig. 1, is a diagrammatic section of the 35 entry portion of a drying or enameling apparatus embodying the present improvements.

Fig. 2, is a companion view of other or discharge portion of the structure.

Fig. 3, is a detail transverse section 40 through an oven section.

Like reference numerals indicate like parts in the different views.

The type of enameling apparatus shown 45 in the drawings and to which the present improvements are applied, is one of very general use in the arts, and comprises a plurality of elongated drying or baking ovens or chambers 1, supported above the 50 floor of the building in horizontally separated relation. The ovens or chambers 1 are of a rectangular form in cross section and are provided with downwardly inclined roof portions 2 at their respective ends. 55 Within said ovens or chambers 1 and at the respective sides of the same, are arranged

heating elements 3, usually of the gaseous fuel fired type, for affording the required heat in the drying or enameling operation.

Dipping or coating tanks 4 and associated drain or drip receiving tanks 5 are arranged intermediate of the ovens 1 and adjacent to the charging end of the initial oven of the plurality of said ovens.

In connection with the ovens 1, dipping tanks 4 and drip receiving tanks 5, an overhead endless carrier 6 is provided, and which carrier extends in a zig-zag course through and between the plurality of ovens to carry in a suspended manner the articles to be 65 coated or enamelled. The endless carrier 6 is preferably of the type in which track wheels 7 travelling on rails 8 are connected together in pairs by transverse axles 9 from which the articles are suspended, with the 70 series of said pairs or units connected together in spaced relation by intermediate sections of chain or the like, and as usual in the present class of apparatus.

The zig-zag or up and down longitudinal 75 travel of the endless carrier 6, above referred to, is effected by the mounting of the endless carrier upon guide sheaves 10 disposed at different points and levels in the apparatus, so that articles suspended from 80 the carrier will receive an angular downward movement into the dipping tanks 4, like angular upward movements from said tanks, an angular downward movement past the drip receiving tanks 5, an angular upward movement into the drying ovens or 85 chambers 1, a horizontal movement through said ovens or chambers, and an inclined downward movement out of said ovens or chambers towards an adjacent dipping tank 90 4 or to the unloading platform 11 of the apparatus. The return path of the unloaded endless carrier is in a direct overhead line, usually above the roofs of the drying ovens or chambers 1 and other described parts.

In connection with the drying or enameling apparatus above described, the present improvements involve detail arrangements 95 and constructions as follows:—

12, designates a supplementary roof arranged above the usual roofs 1' of the plurality of ovens 1 and extending the entire length of the apparatus, to provide in connection with a series of intermediate side walls 13 and bottom walls 14, a shallow 105 chamber 15 above the plurality of ovens or chambers 1 for movement of the returning 110

portion of the endless carrier 6 and materially aid in maintaining said carrier portion in a warm condition so that with a re-entry of such carrier portion into the initial oven or chamber 1 a minimum absorption of heat by the metallic material of the carrier is effected, with a resulting economy in the heating operation of the apparatus. In the preferred form of the invention, the 10 chamber 15 received the products of combustion, heated vapors etc., from the plurality of ovens or chambers 1 through a series of side ducts 16, with the chimneys or uptake stacks 17 connected to the roof 15 of said chamber. With such arrangement the chamber 15 and the portion of the endless carrier moving therein, are maintained in a heated condition in an effective and economical manner.

20 Having thus fully described my invention what I claim as new and desire to secure by Letters Patent, is:—

1. In a series enameling oven of the class herein described wherein the articles are 25 carried by a horizontally arranged endless

carrier through alternately arranged dipping stations and drying chambers, the combination of a series of drying chambers, an endless carrier associated with said chambers, and a longitudinal chamber arranged 30 at the roof of said chambers and adapted to house the return run of the endless carrier.

2. In a series enameling oven of the class herein described wherein the articles are 35 carried by a horizontally arranged endless carrier through alternately arranged dipping stations and drying chambers, the combination of a series of drying chambers, an endless carrier associated with said chambers, and a longitudinal chamber arranged 40 at the roof of said chambers and adapted to house the return run of the endless carrier, said longitudinal chamber having communication with the interior of said chamber 45 and with an uptake stack.

Signed at Chicago, Illinois, this 14th day of February, 1923.

ARTHUR MAEHLER.
